UNITED STATES PATENT OFFICE.

THEODORE SEYB, OF RICHLAND, IOWA.

BACK-PAD TREE.

1,097,992.

Specification of Letters Patent.

Patented May 26, 1914.

Application filed April 11, 1912. Serial No. 690,015.

To all whom it may concern:

Be it known that I, THEODORE SEYB, a citizen of the United States, residing at Richland, in the county of Keokuk and State of Iowa, have invented certain new and useful Improvements in Back-Pad Trees, of which the following is a specification.

This invention relates to harness, and particularly to that portion of harness known as back bands, and is designed to economize leather in the construction of the back pad and pad skirt.

It is a further object of the present invention to provide a joint connection between the back pad tree and the pad skirt.

With the above and other objects in view, this invention consists in the construction, combination and arrangement of parts, all 20 as hereinafter more fully described, claimed, and pointed out in the drawings, in which—

Figure 1 is a top plan view of a back pad tree constructed in accordance with the present invention. Fig. 2 is a side elevation thereof. Fig. 3 is a perspective of the clip connection between the back pad tree and the pad skirt. Fig. 4 is an elevation of the connection between the terminals of the back pad tree and the clips or connections 30 illustrated in Fig. 3.

The back pad tree and joint connection between the back pad tree and the pad skirt form the subject matter of the present invention.

35 The back pad tree comprises a continuous strip of metal made to fit over the back pad, when the back pad is bent to conform to the contour of the horse's back. The terminals of the back pad tree or strip of metal are 40 pierced by transversely arranged openings. A U-shaped member or clevis is mounted in the opening thus formed at each end of the pad tree through the instrumentality of a threaded rod piercing the terminals or 45 arms of said U-shaped member and projecting through said openings. The curved portion of the clevis or U-shaped member is adapted to be engaged by a clip as will hereinafter be more fully described, for the pur-

pose of securing the pad skirt to the back 50 pad tree.

Reference being had more particularly to the drawings, 10 indicates a strip of metal which constitutes the back pad tree, as illustrated in Fig. 2, made to fit over the back 55 pad, when the back pad is bent to conform to the contour of the horse's back. The convex portion 12 is raised to substantially the same plane as the outer surfaces of the beaded edges 11. The terminals 13 of the metal 60 10 are pierced by aligned openings 14 to provide a means whereby the connections between the back pad tree and the skirt may be secured to the back pad tree.

The U-shaped member is connected to each 65 opening 14 through the instrumentality of a threaded rod 16 which is screwed into the terminals of the arms of said U-shaped member 15. It will clearly be seen from this construction, that the U-shaped member 70 15 is pivotally connected to the terminals 13 through the instrumentality of the rod 16 and is dependent therefrom and may assume any angle necessary to create a positive adjustment between the back band and 75 the horse's back.

The curved portion of the U-shaped member 15 is connected to a clip indicated generally as 17 and illustrated in detail in Fig. 3, said clip constituting a connection between 80 the U-shaped member 15, and likewise to the back pad tree 10, and the tug bearers (not illustrated). This clip 17 constitutes a strip of metal bent upon itself as illustrated having the bent portion 18 thereof concave 85 to conform with the curve of the U-shaped member 15. The terminals of the strip of metal forming the clip 17 are reduced as at 19 and are adapted to secure therebetween the terminals of the tug bearers. 90

Having thus fully described my invention, what I claim is new and desire to secure by Letters Patent of the United States, is:—

The herein described back pad tree consisting of a single continuous strip of sheet 95 metal, the terminals of said strip being provided with transverse apertures, U-shaped loops, rods connecting the terminals of the

U-shaped loops, each of said rods extending through the transverse apertures in one end of said tree and through eyes formed on said loops, and clips connected to said U-shaped loops, said clips each consisting of a strip of metal made concave at its upper end to conform to the curvature of the U-shaped loops, and a portion of the side mem-

bers of the clips being reduced and perforated for connection to the tug bearer.

10

In testimony whereof I affix my signature in presence of two witnesses.

THEODORE SEYB.
